UNITED STATES PATENT OFFICE.

JOHN LAWRENCE O'CONNOR, OF PORTLAND, MAINE.

DIVIDERS.

Application filed October 8, 1926. Serial No. 140,302.

An object of the present invention is to provide a pair of dividers so constructed that they are capable of convenient and rapid manipulation for purposes of adjustment 5 with one hand, and are thereby rendered peculiarly suitable for the use of workmen.

A further object of the invention is to provide a pair of dividers so constructed that a full length pencil may be mounted 10 therein, and when worn down so that only a small stub is left, will be still securely retained in position.

Other objects of the invention are to provide a device of this character which will 15 be of simple, practical construction, rugged and durable in use, neat and attractive in appearance and extremely unlikely to get out of order in the ordinary course of usage.

With the above noted and other objects in view, the invention consists in certain novel 20 features of construction and combinations and arrangements of parts, as will be more fully hereinafter set forth and pointed out 25 in the claims. The invention may be more fully understood from the following description in connection with the accompanying drawings, wherein—

Fig. 1 is a view mainly in side elevation 30 of a pair of dividers embodying the present invention, with a portion of one leg broken away and in section for the sake of clearness.

Fig. 2 is an edge view of Fig. 1.

Fig. 3 is an enlarged transverse sectional detail on the line 3—3 of Fig. 1.

Fig. 4 is an enlarged longitudinal sectional detail on the line 4—4 of Fig. 2.

In the drawings I have used the numerals 40 10 and 11 to designate the two pivoted legs of the divider. These legs are connected together at their upper ends in a substantially conventional manner by a pivot stud or screw 12. The upper portion of each leg is 45 angularly offset from the lower portion thereof so that when the dividers are in approximately closed position as shown in Fig. 1, the upper ends of the legs 10 and 11 will converge toward the pivot and the 50 lower ends of the legs will converge toward their free ends.

As is customary in the art, the leg 10 is shorter than the leg 11, and is adapted to have its length supplemented by the attachment 55 of a suitable marking device, such for instance as the lead pencil 13.

Preferably the upper and lower portions of each of the legs while offset relatively to each other are individually straight, so that the pencil 13 may be retained snugly 60 in position within a shallow groove 14 in the outer face of the leg 10 by means about to be described. The means which I have illustrated includes a collar 15 encircling the pencil 13 and a threaded stud 16 carried by the collar and passed through the leg 10. At the inside of this leg the screw is engaged by a clamping nut 17. By tightening the nut 17 it will be understood that the collar 15 is drawn into a recess 18 communicating with the groove 14, and acts to draw the pencil tightly against the bottom of the groove.

Due to the angular shape of the leg 10, a pencil of full length may be used. Even 75 after the pencil has been reduced to a relatively short stub by usage, the stub end may still be firmly clamped by the collar 15 and its associated nut 17.

The lower or free end of leg 11 is pointed 80 at 19 or may carry a conventional penetrating pin or point, this point serving as a center about which the sharpened end 20 of the pencil 13 may be swung.

An arcuate sector bar 21 struck on a curve 85 of which the pivot 12 is the center is anchored to the leg 10 and accommodated in a slot 22 in the leg 11 of the dividers. Bar 21 may have a reduced threaded end 23 passed through the leg 10 and detained by a nut 90 24. If desired a flat spring 25 anchored to the leg 10 engages a shoulder 26 on the bar 21 and retains the bar against movement relatively to the leg 10.

For locking the two legs of the divider in 95 any position of relative separation there is provided a cam latch member 27 pivoted at 28 in the slot 22 and formed with a cam face 29 adapted to engage the arcuate bar 21.

A torsional spring 30 includes a pair of 100 legs 31 and 32, the former of which is anchored at 33 in the slot 22, and the latter of which bears against the tail end of the cam latch 27 and urges it into clamping relation with the bar 21.

It will be noticed that the tail of the latch 105 projects laterally from the outer surface of the arm 11 and may be conveniently manually pressed inwardly against the action of spring 30 when it becomes desirable to release the bar 21 and permit comparatively free pivotal movement of legs 10 and 11.

- The construction above described permits convenient operation of the device with one hand. Leg 11 is preferably grasped with the thumb and forefinger in such a manner that 5 the thumb may be used for depressing the tail piece of the cam latch. This will leave the other three fingers of the hand free to swing the leg 10 in either direction for purposes of adjustment.
- 10 While I have illustrated one of the preferred embodiments of the invention, it is to be understood that various changes and alterations might be made in the general form and arrangement of parts described 15 without departing from the invention. Hence I do not wish to limit myself to the details set forth, but shall consider myself at liberty to make such changes and alterations as fairly fall within the spirit and scope 20 of the appended claims.

Although in the specification and claims I have referred to the tool of the present invention simply as a divider, it is to be understood that the term "divider" is meant to be 25 broad enough to cover calipers and other tools or instruments having the same generally similar construction and function.

I claim:

- 30 1. A pair of dividers including pivotally connected legs of different lengths, the free end of each leg being angularly offset with respect to the pivoted end thereof, and the longer leg being pointed, means for clamping a marking implement against the outer

face of the free end of the shorter leg, said 35 leg section having a groove in its outer face to receive the marking implement, said clamping means including a ring encircling the marking implement and a screw working through said shorter leg for adjusting the 40 ring laterally to move the marking implement against the bottom of the groove.

2. A pair of dividers including pivotally connected legs, a sector bar carried by one leg and working through a slot in the other 45 leg, and spring latching means carried by said last mentioned leg engaging the bar to retain the legs in any position of pivotal adjustment, said latching means including a pivoted cam member mounted in said slot 50 in the leg and a spring in the slot for rocking the cam member into binding engagement with the bar.

3. A pair of dividers including pivotally connected legs, a sector bar carried by one 55 leg and working through a slot in the other leg, and spring latching means carried by said last mentioned leg engaging the bar to retain the legs in any position of pivotal adjustment, said latching means including 60 a pivoted cam member mounted in said slot in the leg and spring rocked into binding engagement with the bar, and an operating tail piece on the cam member projecting 65 beyond the slot, whereby the cam piece may be manually rocked out of binding engagement with the bar.

JOHN LAWRENCE O'CONNOR.
